UNITED STATES PATENT OFFICE.

CHARLES B. MOORE, OF EVANSTON, ILLINOIS, ASSIGNOR TO AMERICAN ARCH COMPANY, OF NEW YORK, N. Y., A CORPORATION OF NEW YORK.

LOCOMOTIVE BOILER FURNACE.

1,115,958.

Specification of Letters Patent.

Patented Nov. 3, 1914.

Application filed February 14, 1912. Serial No. 677,566.

To all whom it may concern:

Be it known that I, CHARLES B. MOORE, a citizen of the United States, and a resident of the city of Evanston, county of Cook, and State of Illinois, have invented certain new and useful Improvements in Locomotive-Boiler Furnaces, of which the following is a specification.

My invention relates to improvements in locomotive boiler furnaces and has special reference to improvements in refractory baffles or deflecting walls commonly called arches for the fireboxes of locomotive boilers.

The general objects of my invention are to provide an improved wide span refractory arch which may be quickly and easily installed in locomotive boiler furnaces and which shall be of relatively light weight and low cost; to provide an arch which shall be so constructed that repairs can easily be made thereto whenever necessary; to provide a sectional arch parts of which, though to some extent interlocked, can be removed without disturbing the remainder, to afford convenient access to the side sheets and the flue sheet of the firebox for repairing same; and to provide an arch of such a form that it assists in mixing and igniting the firebox gases and the particles of fuel and smoke carried thereby.

A further and special object of my invention is to provide an improved arch of the character herein indicated which shall be adapted for use in locomotive fireboxes having a wide span, as in cases where there are no intermediate supporting means between the sides thereof.

A still further object of my invention is to provide refractory span and panel bricks of small size for passing through the doorway of a locomotive firebox and formed to fit together and interlock, panel bricks with span bricks, to form an arch of the character described which shall be substantially integrally for operative service and multiparite for repairs.

My invention consists in the several improvements, the various features of construction and the combinations of parts by means of which the above and other objects are attained, and all as hereinafter fully described and particularly pointed out in the claims.

In the accompanying drawings illustrat-

ing a preferred embodiment of my invention: Figure 1 is a vertical central longitudinal section of the firebox; Fig. 2 is a horizontal longitudinal section on the line 2-2 of Fig. 1; Fig. 3 is a vertical cross section of the firebox back of the arch on the line 3-3 of Fig. 1; Fig. 4 is a cross section of the arch on line 4-4 of Fig. 1; Fig. 5 is a cross-section of the arch on line 5-5 of Fig. 1; and Fig. 6 is an enlarged fragmentary sectional view on the line 6-6 of Figs. 2 and 4.

Although I have chosen to illustrate my invention as embodied in a front arch, I wish it to be understood that my invention is not thus limited, but is capable of embodiment in arches occupying various positions in the firebox and having somewhat different functions.

A locomotive firebox, as illustrated in the drawings, comprises a flue sheet 2, side sheets 3, a rear sheet 4 and a crown sheet 5. A grate 6 is provided in the lower part of the firebox and a fuel door or opening 7 is provided in the rear sheet. Leading forward from the flue sheet 2 are a plurality of flues 8 by which the gases of combustion are conducted away from the firebox. A front arch as ordinarily used in a firebox is mounted in an inclined position between the fuel bed and the flues with its lower edge substantially abutting the lower portion of the flue sheet. Openings are usually provided between the arch and the flue sheet for the downward escape of cinders and other material that would otherwise tend to collect on the upper side of the arch.

The usual purpose and function of a front arch, as ordinarily installed is to baffle or obstruct the direct flow of the fuel gases from the fuel bed to the flues and cause said gases to flow backward and forward in the firebox and thereby distribute their heat over the entire interior surface of the firebox and especially over the whole length of the crown sheet.

My improved arch is characterized by spaced pairs of complementary refractory arch span bricks longitudinally ribbed and grooved on their upper sides and extending from side to side of the firebox, in combination with a plurality of refractory cover bricks or roof panels supported thereby and grooved on their undersides adjacent to their transverse edges, to interlock with the cor-

responding ribs and grooves on the span bricks.

In the specific embodiment of my invention illustrated in the drawings, the deflector arch 9 as a whole consists of a plurality of pairs of span bricks A and a plurality of intermediate bridging rows of panel bricks B resting upon and interlocking therewith. Each of the span bricks A is suitably formed on its lower outer end A' to rest upon suitable supporting shoulders or lugs 10 secured to the side sheets 3. The upper ends A² of said span bricks are preferably beveled to abut substantially squarely together and are provided with suitable engaging or interlocking means as tongues and grooves preferably arranged as a half tongue A³ and a half groove A⁴ on each brick adapted to coact with the corresponding half tongue and groove on the opposite brick. Each of the span bricks A is provided with suitable means for definite engagement with the panel bricks B, said means preferably consisting of shoulders or ribs A⁵ formed longitudinally along the outer edges of the upper side of the span bricks A and adapted to coact with corresponding means as downwardly facing grooves B' on the undersides of the overlapping ends B² of the panel bricks B. Thus deflector arch 9 consists of two upwardly and convergently inclined sides, roof portions or halves abutting together at their upper edges and supported at their lower edges in substantial contact with the side sheets 3. Each of these portions or halves is composed of a plurality of span bricks A and a plurality of panel bricks B as described.

In order to secure simplicity of form and corresponding facility to manufacture and use the parts constituting the subject matter of my invention, I prefer to form the span bricks A with a substantially rectangular cross-section and with a single broad longitudinal hollow or groove A⁶ on its upper side bordered by the lateral upstanding integral ribs A⁷ of rectangular cross section. I form the hooked or interlocking ends of the panel bricks B of full thickness with square corners and rectangular cross section, and form a rectangular groove B' in the underside thereof adjacent to the edge both at the forward and rear ends, of a depth corresponding with that of the groove A⁶ in the span bricks, and wide enough to readily receive the upwardly projecting rib A⁷ of the span brick. I make the groove A⁶ amply wide enough to receive the double row of hooks or ribs B³ bordering the grooves B' of the adjacent coacting panels B lying on opposite sides of an intermediate pair of span bricks. The panel groove B' is preferably formed only wide enough to give ample clearance for the rib A⁷ of the

span brick. This form and arrangement of the interlocking means assures a definite interlocking relation between the span bricks and the panel bricks. The panel bricks B are preferably of plain rectangular slab-like shape, and are preferably made as large as may be readily passed through the door of the firebox without being too heavy for convenient handling. As these arches are designed for use in particularly wide spans, it is generally preferable to arrange the panels in transverse rows of two or more on opposite sides of the arch between adjacent pairs of span bricks, such rows being in alignment and forming a continuous row extending from side to side of the firebox. Each of the panel bricks B is made relatively light and thin in order that the arch as a whole may be as light as possible.

As the arch is inclined upwardly and rearwardly the apex only of the forward or lower end of the arch engages the flue sheet as at the point 12. The front edges of the arch diverge slightly away from the flue sheet in both directions from the central point 12, leaving openings 13 between the arch and the sheet through which any materials deposited on the upper side of the arch may escape downwardly upon the fuel bed.

As the undersurfaces of the span bricks A are inclined corresponding to the inclination of the arch, the bearing lugs 10 therefore are arranged in an inclined row. Supplementary lugs 10' are provided on the side sheets adjacent to the lugs 10 just in front of the position for the outer ends A' of the span bricks A to prevent the latter from slipping forward off from the lugs 10.

By the construction which I have described, the transverse span bricks A and the covering panel bricks B form large transverse downwardly facing pockets and baffles adapted to retard and mix the firebox gases as they flow upwardly and rearwardly thereunder. Moreover, each of the panels B is provided with a supplementary downwardly facing pocket B³ on its underside formed deep and wide enough to leave only light thin walls. This structure renders the panel light in weight without materially impairing its strength as its side walls serve to reinforce it. These relatively small pockets, positioned in the roof of the larger main pockets, assist materially in the mixing of the firebox gases. Arches made in accordance with my invention serve to mix the gases and tend to prevent and break up stratification thereof and to retard the flow thus facilitating and insuring more complete combustion of the fuel and prevention of the formation and escape of smoke.

The purposes of the arch are usually answered by constructing the arch long enough

to extend substantially to the center of the firebox, in which case two rows of panels usually suffice, though in some cases a shorter arch consisting of a single row may be preferable.

In constructing my improved arch, I first place a pair of span bricks A in position adjacent the flue sheet 2 with their outer ends A' resting on the lugs 10 provided therefor. I next place a similar pair of span bricks on other lugs a suitable distance to the rear of the first pair and then place the panel bricks B thereon with the grooves on said panels and the corresponding ribs on the span bricks in engagement.

As modifications of the above described embodiment of my invention will readily occur to those who are skilled in the art, I do not wish to be limited to the specific form of structure herein set forth.

Having thus described my invention, I claim as new and desire to secure by Letters Patent:

1. In a locomotive firebox, an inverted V-shaped refractory arch structure suitably supported at its lower or outer side edges and consisting of two oppositely inclined roof portions wedgingly abutting at their upper or inner adjacent edges, each of said roof portions being composed of a plurality of transverse rows of refractory panel bricks having downwardly facing grooves formed in the under sides of their transversely extending edges, in combination with a plurality of span bricks extending transversely of the firebox beside and partly beneath said panel bricks to support them and having upwardly projecting ribs on their front and rear edges to engage the grooves on said panel bricks to hold the said panel and span bricks in definite relation.

2. In a locomotive firebox, a wide span arch comprising a plurality of pairs of complementary supporting span bricks, the bricks of each pair being wedgingly positioned end to end in arched position and extending transversely between the side sheets, and one or more transverse rows of panel bricks with their front and rear edges resting on adjacent supporting spans, said span bricks each having an upwardly facing central longitudinal groove on its upper side and said panel bricks each having a downwardly facing groove in the under side of each of its bearing edges, the coacting edges of each brick fitting into the corresponding grooves of the adjacent bricks.

3. In a locomotive firebox having a flue sheet at the front end, a rear sheet having a doorway therein at the opposite end, side sheets on opposite sides and suitable arch supporting means secured to the side sheets at the forward end of the firebox adjacent to the flue sheet, a wide span refractory arch resting at its outer edges on said supporting

means, said arch comprising a pair of upwardly and convergently inclined sides abutting at their upper edges in arched relation and suitably formed at their lower outer edges for resting upon said supporting means, and 70 sides each consisting of alternate span bricks and rows of panel bricks resting thereon and interlocking therewith at their edges, the respective upper and lower engaging edges of said span and panel bricks being correspondingly ribbed and grooved for detachable positive engagement with each other, and the corresponding span bricks of opposite sides of the arch being formed to fit positively together in end-to-end abutment. 80

4. A refractory panel brick for locomotive firebox arches consisting of a substantially plain rectangular slab of a size convenient for passing through the firebox door and having a downwardly facing pocket 85 formed in its underside and having a downwardly facing groove extending across the under side of each end forming thereon substantially an anchoring hook for securing the brick in place in the arch. 90

5. In a locomotive firebox a wide span refractory arch comprising a plurality of pairs of complementary span bricks, the members of each pair being wedgingly positioned end to end in arched relation and extending transversely between the side sheets, said pairs being spaced apart, and a plurality of panel bricks resting thereon, said span bricks having projections integral therewith at their edges to detachably interlock with complementary projections formed integral with the edges of the panel bricks and thereby interlock the said panel bricks and the said span bricks in determined relative position. 100

6. In a locomotive firebox an arch suitably supported at its side edges and consisting of two upwardly and convergently inclined portions abutting together at their upper edges, each of said portions being composed of one or more transversely positioned rows of thin slab-like panel bricks and a plurality of long, narrow span bricks lying between and at the sides of said rows of panel bricks partially beneath and in cooperative supporting relation therewith, said panel bricks and span bricks having formed on the under and upper sides respectively of their adjacent edges integral complementary projections and recesses positively retaining the panel and span bricks in definite position. 110

7. In a locomotive firebox an inverted V-shaped refractory arch structure suitably supported at its lower or outer side edges 125 and consisting of two oppositely inclined roof portions wedgingly abutting at their upper or inner adjacent edges, each of said roof portions being composed of a plurality of transverse rows of refractory panel 130

bricks having recesses in the under sides of their transversely extending edges, in combination with a plurality of span bricks extending transversely of the firebox, adjacent to and partly beneath said panel bricks supporting them, and having upwardly extending projections on their forward and rear edges interlocking with the said recesses in the span bricks to hold the said

panel bricks and span bricks in definite relative position.

In testimony whereof, I have hereunto set my hand this 24th day of January, 1912, in the presence of two subscribing witnesses.

CHARLES B. MOORE.
